UNITED STATES PATENT OFFICE.

HERMAN SCHLAICH, OF LONG ISLAND CITY, NEW YORK, ASSIGNOR, BY MESNE ASSIGNMENTS, TO THE KINGSLEY-MILLER COMPANY, OF CHICAGO, ILLINOIS, A CORPORATION OF ILLINOIS.

RADIATOR CAP.

Application filed March 4, 1924. Serial No. 696,812.

This invention relates to an improvement in caps for the filling necks of the radiators of water cooled internal combustion engines for automobiles or the like.

5 It is one of the objects of the invention to provide a radiator cap which is adapted especially for carrying a motor heat indicator of a well known type and is so constructed that heat indicators of different sizes can be 10 mounted and centered upon the cap without necessitating a change in the size or construction of the cap.

Another object of the invention is to provide a hinged radiator cap in which the pivot 15 or hinge is located substantially within the confines of the cap so that the symmetrical appearance of the cap will not be marred by projecting hinge lugs or the like as in the prior radiator caps of this type. Another object 20 of the invention is to provide a means for securing the packing washers between the cap and the filling neck so that they cannot be forced out of their normal position when pressure is applied to make fluid tight joint 25 between the filling neck and the cap.

Various other objects and advantages will appear as the description of the invention proceeds.

This application constitutes a continuation 30 in part of my co-pending application 607,937 filed December 20, 1922.

Referring now to the drawings which illustrate preferred forms of embodiment of the invention,

35 Figure 1 is an elevation of the cap as it appears from the front of the automobile showing a heat indicator of a well-known type mounted thereon.

Figure 2 is a sectional view of the cap 40 shown in Figure 1, showing details of the construction thereof.

Figure 3 is a detail sectional view of the cap provided with an adapter for fitting the same on an exteriorly threaded radiator neck.

45 Figure 4 is a sectional view showing how the cap is mounted on the radiator neck of a Ford automobile.

Figure 5 is a view similar to Figure 1 showing the heat indicator removed and the 50 hinged portion of the cap in raised position.

Figure 6 is a bottom plan view of the cap.

The cap comprises a circular body portion 1

provided with oppositely extending projections or arms 2 which terminate in enlarged portions 3, adapted to carry transparent 55 crystals 4 through which any suitable insignia carried in the enlargement 3 are visible as is more fully described in my co-pending application Serial No. 607,937, referred to above.

A cover 5, hinged to the body portion at 6 provides a ready means for opening and closing the cap when it is desired to put water 60 into the radiator.

A depression 10 is found in the top of the cover 5 at approximately the center thereof and a hole 11 is made through the cover at the center of the depression for permitting the stem 12 of the heat indicator 13 to project through the cover and into the top of the 70 radiator. To permit the same cap to be used with heat indicators of different sizes and types the depression 10 is made the same diameter as the base 14 of the smaller size heat indicator so that when the nut 15 is screwed 75 onto the stem 12 of the indicator the base 14 will be drawn into and centered in the depression 10, as shown in Figure 2. The hole 11 is made of substantially the same diameter as the stem 12^a of the larger size heat indicator so that although the base 14^a of the larger 80 size indicator does not fit within the depression 10, the indicator is securely held centered on the cap by the close fit between the stem 12^a and the hole 11 as illustrated in Figure 4.

To latch the cap in closed position the body 1 is provided with a lug 6^a to each side of which is pivoted a link 7, as shown in Figures 2, 5 and 6. A cam lever 8 is pivoted between 90 the links 7 at their opposite end and is adapted to slip over and engage the lug 9 on the cover to hold the same tightly closed.

To permit the end of the stem 12 to clear the front portion of the opening 16 through 95 the cap, when the lid 5 is swung open or closed on the pivot 6 the opening 16 is located eccentric to the body of the cap (see Figures 5 and 6) so that the ledge 17 is wider at the rear of the cap than at the front. It will be observed that the eccentric location of opening 16 in the cap body permits the hinge 6 to be arranged within the body outline in such manner that the body contour is not broken by 100

an unsightly projecting hinge. An annular groove 18 in the top of this ledge supports a soft rubber ring 19, which contacts with the eccentric level or ridge 20 on the underneath portion of the cover to make a fluidtight seal between the cover and body portion when the cover is closed.

The features referred to in the preceding paragraph are disclosed and claimed in my pending application Serial No. 15,710, filed March 16, 1925 for radiator caps, which application is a continuation in part of this application.

The cap may be directly secured to a shouldered radiator neck as illustrated in Figure 4, or it may be attached to straight necks by means of applied shoulder pieces as illustrated in Figures 2 and 3 so that the one size and type of cap may be fitted to various radiator necks.

In Figure 4 the cap is shown as fitted directly upon the filling neck 21 of a Ford automobile radiator and secured thereto by the set screws 22 which engage the underside of the neck flange or shoulder 23. A packing washer 24^a is inserted between the ledge 17 and the top of the filling neck 21, and to prevent this washer from being pushed out of position when the cap and neck are forced together to make a fluidtight seal, a shallow groove or channel 25 is made in the ledge 17 near the outer portion thereof so that when the washer 24^a is compressed between the neck 21 and the cap 1, a portion of the washer 35 will be pushed into the groove 25 and will prevent the washer from being squeezed out from between the neck and the cap, thus effecting a water and steam tight joint and effectively disposing of the difficulties commonly experienced with narrow gasket bearing surfaces.

In order to lock the cap 1 and the heat indicator 13 against theft angular holes or sockets 22^a (Figure 3) are provided in the set screws 45 22 and in the nut 15. The wrench openings in these set screws 22 may be plugged with lead shot or the like 22^b after the screws have tightened, so that the screws may be loosened only by first digging out the shot.

To fit the cap on internally threaded radiator necks as shown in Figure 2 the shouldered member 26 may be used. This member is threaded at its lower end 27 to screw into the threads in the radiator neck 21^a, a set screw 22^d being provided for locking the sleeve to the neck. The upper end of member 26 fits within the opening of the cap, and is provided with a beveled surface 28 against which the set screws 22 of the cap may bear 55 to lock the cap in place.

The adapter 29 shown in Figure 3 may be used to attach the cap to externally threaded radiator necks 21^b. This adapter comprises an internally threaded portion 30 which 65 screws upon the radiator neck and an in-

wardly extending flange 30^a which rests upon a washer 31 to make a fluid tight seal between the neck and the adapter. The cap 1 fits over the adapter 29 and is secured thereto by the set screws 22 which engage the beveled portion 32 of the adapter. The washer 24 provides a fluid tight seal between the adapter and the cap.

It is obvious, of course, that the size or shape of the adapter may be varied so as to enable the cap to be attached to filling necks of different sizes or shapes from those shown.

That the convenience, appearance and general usefulness of my improved cap may be further enhanced, I have also provided the improved construction features shown in Figures 5 and 6.

In compliance with the patent statutes, I have illustrated and described certain preferred embodiments of my invention but it is to be understood that various modifications can be made without departing from the spirit of the invention or the scope of the appended claims.

I claim:

1. A radiator cap attachable to a radiator neck having means thereon forming a flange or collar, comprising a cap body having a skirt portion surrounding and covering the flange or collar, and means carried by said skirt portion and operable against the lower face of said flange or collar with a camming action to clamp the cap body down upon the neck.

2. A device for retaining a radiator cap body to a shouldered radiator neck, comprising a cap body fitting over and contacting with the upper surface of said shoulder, a further portion of said body extending below said shoulder and means mounted in the said further portion and projectable therethru to engage the lower surface of said shoulder with a camming action to press the cap down upon the neck.

3. In retaining devices for radiator caps, a shoulder ring locked to the radiator neck, a cap body having an internal bore fitting over said ring and projecting therebeyond, and means mounted in the projecting body portion operable to engage said shoulder with a camming action, for clamping the cap to the ring and to the radiator neck engaged thereby.

4. In retaining devices for securing radiator caps to shouldered radiator necks, a cap body having a bore fitting over the top and shoulder of said neck, securing means simultaneously engaging said body and the underside of said shoulder, to draw said body downward upon said neck and to prevent relative motion therebetween, and means for preventing the retraction of the securing means.

5. In combination, a radiator cap constructed for attachment to a shouldered radiator neck, comprising a body arranged to fit

around such radiator neck shoulder and body retaining means carried by the body and engageable with the shoulder for holding the body in place, and an adapter removably inserted within the cap body and threadable onto a straight radiator neck, said adapter being constructed to cooperate with the body

retaining means similarly to the shoulder of the shouldered radiator neck for retaining the body in place.

In testimony whereof I have affixed my signature to this specification.

HERMAN SCHLAICH.
